UNITED STATES PATENT OFFICE.

CHARLES W. PETERSON, OF ANN ARBOR, MICHIGAN.

LOUD SPEAKER.

Application filed December 10, 1924. Serial No. 755,055.

To all whom it may concern:

Be it known that I, CHARLES W. PETERSON, a citizen of the United States, and a resident of Ann Arbor, in the county of Washtenaw and State of Michigan, have invented certain new and useful Improvements in Loud Speakers, of which the following is a full, clear, and exact description, reference being had to the accompanying drawing, forming part of this specification.

My invention relates to reproducing devices for radio use, known as "loud speakers."

In United States Patent No. 1,491,208, dated April 22nd, 1924, now in the reissue division, I have shown a device for transposing electric vibrations into sound vibrations, which is essentially, a pair of E-shaped magnets, with an armature of resilient nature held between the central arms, which are formed as a north and a south pole. The oscillating flux is impressed on the armature itself, which is of magnetic material, both flux creating coils impressing the same polarity on the central part of the armature. The center lies between the two central arms of the magnets, and vibrates as the flux varies. The vibration in the form shown is transmitted by a rod mounted on the armature, which rod extends through a hole in one of the magnets.

The object of my present invention is to improve upon the mechanical features of the device of my loud speaker. I have shown a conical diaphragm, and my devices are designed to give best results with such a diaphragm, but it will be understood that this is not the only type of diaphragm which can be used.

Among my objects is the improvement of the link system transmitting the motion of this armature to the diaphragm. The ends of the armature are still held between the yokes or side arms of the two magnets, but the center of the armature is in my new improvement connected to one arm of a pivoted lever. This lever in turn transmits the motion of the armature to the diaphragm at the proper lever arm distance from the fulcrum point. In the type shown in the drawings, the long lever arm is connected to the armature and a short lever arm, at right angles to the first, is connected to the center of a cone diaphragm giving a motion of less amplitude and greater force to the diaphragm than that of the armature itself.

This reduction of motion and increase of force is very desirable in connection with cone type diaphragms. Having the two lever arms at right angles as shown permits of a more compact and efficient construction than if the two were in line. In case the two lever arms are equal the diaphragm will vibrate with the same amplitude as the armature, the same as when the two are connected by a straight rod link, but the lever link has greater sturdiness and various constructional advantages in my device.

Another of my objects is to provide simultaneously a simple way to adjust the armature into its central position in the air gap, and a simple and efficient fulcrum for the lever. This object I have accomplished by the use of a resilient spring fulcrum, a screw and a depression in the mounting surface so arranged that while tightening the screw the air gap is adjusted.

It is my object with relation to the structure to be used, to make it simple, and effective, and hence economical of production, easy to repair, and of great permanence in use.

I accomplish my object by that certain construction and arrangement of parts to be hereinafter more specifically pointed out and claimed.

Referring now to the drawing forming part of this specification:

Figure 1 represents a front perspective view of my assembled device.

Figure 2 represents a vertical section taken along the lines 2—2 looking in the direction of the arrows in Figure 1.

Figure 3 represents a front view of the armature box 3 with the cover plate and the magnet cover of insulating material removed, as on the line 3—3 of Figure 2.

There is provided a base 1 which for ornamental reasons may be oval. From the base an upright supporting member 2 divides into two arms 2^a in a Y-shaped formation. The upper arms of the Y are joined with a horizontal piece 3, on which is supported the armature box 4. From the position where the horizontal piece joins the upright arms, two upwardly extending arms 5 support the reproducer cone 6 which in the example herewith shown is of parchment. It may, however, be of any vibrant inexpensive material. In assembling the armature box, a plurality of magnets 7 which are E shaped and have negative poles 7^a at the end

of the central member of the E are placed side by side within the lower half of the box 4 with the extended sides of the E up. They fit closely in between channels 8 mounted vertically in the box, and they are further held in fixed position by the exterior insulating plate 9, which cover the flat faces of the front and back magnet sections. The armature 10 with an armature coil 11 slipped over each end is then slid down channels 8 so that the armature coils are held in place by the arms of the magnets and the edge of insulating plates 9. The upper sections of the permanent magnets 12 with positive poles 12^a and the insulating plates 13 are then slid into place down the channels 8 and clamp the armature and coils in place. The ends of the armature carry spacers 13^a which provide an air gap between magnets 12 and the armature and also act as resilient pivots for the ends of the armature. The magnets, armature and coils are then all clamped firmly in place by a flat spring 14 which is held down by pins 15 and presses uniformly on all of the magnets 12 and insulating plates 13 through pad 16. The central arms 12^a of the laminated magnet with positive poles and the central arms 7^a of the laminated magnet with negative poles are recessed, as shown at 18 and 19. Into these recesses the long end of a fulcrum lever 20 fits and the armature 10 slides into a slot 21 in this lever and is held securely therein. The fulcrum of the lever is mounted horizontally on a thin strip of vibrant metal 22 which fits into a cup shaped depression 23 on a supporting lug 24 which is formed on a bracket extending from the supporting arm 3 back toward the center of the resilient cone 6. The vibrant support piece 22 has a screw 25 which fits through a hole positioned vertically in it. Adjustment on this screw forces the metal of the strip under the head of the screw into the cup shaped depression which causes the end where it is attached to the lever to spring up. This adjustment screw permits the movement of the center of the armature into the exact central position between the poles of the laminated magnets. The shorter fulcrum arm extends in a thin wire or rod 26 through the center of the reproducing cone or horn and is fixed therein by a sleeve and set screw 27, held in place by the metal tips 28 on the cone.

The operation of the device is as follows: Magnetic excitation is brought about in the central portion of the armature, which has been previously adjusted to a position equidistant between the positive and negative poles of the laminated magnets, by the alternating current flux induced by the audio frequency oscillations passing through the armature coils. The armature and field fluxes react causing displacement of the armature

from its central position. The vertical vibrations of the armature are transferred throughout the long arm of the lever to the short end where their tonal force is greatly increased by the lever operation.

Having thus described the construction by which I secure greatly increased quality in a loud speaker, what I claim and desire to secure by Letters Patent, is:

1. In an electric sound reproducing apparatus the combination of magnet elements, opposite poles thereof placed to form an air gap between, an armature within the air gap, coils surrounding the armature, a lever connected to the center of the armature, a resilient member providing the sole fulcrum of the lever, and means to bend the resilient member for adjustment of the armature position.

2. In a device of the character specified, laminated magnet elements, opposite poles thereof placed to form an air gap between them, an armature in the air gap, coils surrounding the armature, a long arm of a lever retaining the armature in interpolar position, an adjustable resilient member providing the sole fulcrum of the lever and a sound intensifying member actuated by the short arm of the lever.

3. In an apparatus used to convert audio electrical variations into sound vibrations, or sound vibrations into electrical excitations, the combination of magnet elements, opposite poles thereof forming an air gap between them, an armature in the air gap, the long arm of a lever actuated by the armature, a resilient member forming the sole fulcrum of the lever, and the short arm of the lever connected to a sound vibrating diaphragm.

4. In a radio loud speaker, an armature between opposing poles of magnet members, a lever mounted on the armature, said lever connected with a resilient member, and said resilient member connected with a sound amplifying diaphragm, and a resilient element as part of the lever and providing the fulcrum thereof.

5. In a device for converting audio electrical variations into sound vibrations or sound vibrations into electric excitations, a sound amplifying diaphragm, a receiver mounted centrally thereof, having an electrically actuated armature, a member connected to the sound amplifying diaphragm, a lever connected to the member, a resilient element constituting the sole fulcrum for the lever, and the other lever arm connected in the box to the armature.

6. An electro-sound converting apparatus comprising the opposed E-shaped field magnets with the center pole separated by an air gap and magnetized in that one center pole is N and the other S, an armature whose center plies in the air gap between the center

field pole and whose ends are magnetically close to the outer arms of the E-shaped field magnets, armature coils around the parts of the armature between this center pole and arm of the field magnet, a diaphragm, and a lever link system to transmit the vibration of the armature to the diaphragm at desired amplitude or conversely to transmit the vibration of the diaphragm to the armature at desired amplitude.

7. A loud speaker comprising two opposed E-shaped field magnets with the center poles separated by an air gap and magnetized N and S respectively, a resilient armature whose center plies the air gap between the center field poles and whose ends are magnetically close to the outer arms of the E-

shaped magnets, armature coils around the portions of the armature between the center pole and arms of the field magnet, a cone 20 diaphragm, and a lever link system to transmit the armature vibrations to the apex of the cone at reduced motion and greater force.

8. In an apparatus used to convert audio electrical variations into sound vibrations, or sound vibrations into electric excitations, the combination of a magnet element, opposite poles thereof forming an air gap between them, an armature in the air gap, a diaphragm and a right angled link member 25 30 connecting the armature to the diaphragm and fulcrumed substantially at the apex of said right angle.

CHARLES W. PETERSON.
